AUGIE L. HANSEN, OF EVANSTON, ILLINOIS, ASSIGNOR TO JUSTRITE MANUFACTURING COMPANY, OF CHICAGO, ILLINOIS, A CORPORATION OF ILLINOIS.

METHOD OF BURNING ACETYLENE AND SIMILAR HYDROCARBON GASES FOR ILLUMINATING PURPOSES.

1,296,507.

Specification of Letters Patent.

Patented Mar. 4, 1919.

Application filed November 25, 1916. Serial No. 133,316.

To all whom it may concern:

Be it known that I, AUGIE L. HANSEN, a citizen of the United States, and a resident of Evanston, in the county of Cook and

5 State of Illinois, have invented certain new and useful Improvements in Methods of Burning Acetylene and Similar Hydrocarbon Gases for Illuminating Purposes, of which the following is a specification.

10 My improved method has been developed in connection with and is particularly applicable to the burning of acetylene gas but it may be made use of in connection with other hydrocarbon gases and particularly those 15 which are rich in carbon and with which carbonization presents practical difficulties.

My object is to provide a method by which the flame, if accidentally extinguished, will be automatically and immediately re-lighted.

20 A further object is to provide a method by which a highly efficient illuminating flame may be secured, having the property to a marked extent of resisting the tendency to become extinguished by sudden currents or

25 more or less continuous drafts of air.

I have developed my improved method particularly in connection with so-called acetylene miners' lamps. These lamps are small light structures adapted to be carried 30 on the caps of miners and provided with a carbide container supplied with about an ounce and a half of carbide and with a water receptacle above the same by which water in very small quantity is fed to the carbide so

35 as to generate acetylene gas, the latter being conveyed to a small burner surrounded by a reflector and located on the outside of the water receptacle. Although these miners' lamps are very small and compact and the

40 conditions under which they operate are apparently unfavorable, they burn with astonishing regularity for from two to two and one-half hours for each charge, generating the acetylene gas at a pressure of about

45 an inch and a half of water, although sometimes the pressure varies quite widely from the normal figure.

Other miners' or portable lamps using calcium carbide, of a larger type adapted to 50 be carried by hand or supported from the timbers of the mine, are used, operating on

the same general principle but with larger charges of water and carbide so as to burn for a full shift of from ten to twelve hours.

In mines where open flame lamps can be 55 safely used the acetylene lamp has found a large field, owing to its lightness, convenience, safety, economy of operation and superior illumination. Owing, however, to the small gas pressures used, the flames are relatively sensitive and in consequence whenever 60 blasting takes place in the mines the momentary increased pressure is very likely to extinguish the flames by backing up the gas in the tip. This necessitates re-lighting the 65 lamps, which operation may sometimes have to be performed a great many times a day. Furthermore, in mine operations there are drafts and blasts of air constantly circulating, due to the opening and closing of air 70 traps, the passage of trains and conditions arising from artificial ventilation and other causes; and these conditions also result in frequently extinguishing the flames, requiring 75 re-lighting.

With my improved method I cause the burning gas to develop sufficient heat in a body of refractory material located sufficiently close to the gas stream as to cause the same to be ignited in case the flame has 80 become extinguished. I am, of course, aware that so-called re-lighting devices have been heretofore suggested in which a body of refractory material has been located very close to the flame so as to become heated thereby 85 and operate to relight the gas stream if the flame is extinguished; but such devices have not been commercially successful, for the reason that the re-lighting device, being outside of the path of the gas stream, fails to 90 re-light the latter under ordinary conditions. With such a device it would be impracticable in the burning of acetylene or similar gas to locate the body of refractory material so close to the gas stream as to 95 provide for effective re-lighting, because in that case it would be located within or too near the flame, which would cause it to be rapidly coated with carbon so as to impair its heating qualities and at the same time 100 interfere with the illumination. If such an igniting device were in the form of a ring

through which the flame projected it would soon become entirely closed by the accumulation of carbon.

With my improved method I have discovered that it is possible to burn acetylene gas in two distinct but connected zones, the first being used for heating the re-lighting element without carbonization so that it may be located as a ring through which the gas stream passes, and the second providing for the necessary illumination. In other words, with my improved method I cause the gas to be first burned as a non-illuminating, non-carbonizing blue flame which comes into contact with the re-lighting device made of refractory material so as to heat the same, and from there on the gas is burned as a luminous flame, corresponding substantially to those now employed. Preferably, my improved method is carried out by suitably modifying the construction of the tip, whereby the flame will be subdivided into a non-illuminating heating portion and a luminous or lighting portion. For carrying the method into effect I prefer to make use of a tip such as is claimed in my co-pending application, Serial No. 133,315, filed November 25th, 1916. The tip is made of so-called lava or other refractory material having a very fine orifice through which the gas stream projects and in advance of which is a heating chamber formed with an opening at its extreme end considerably larger than the gas orifice. Between the heating chamber and the gas orifice the bore is somewhat increased over the latter and intakes are provided to feed to the gas a limited supply of air to produce a Bunsen effect. The resulting blue flame is therefore projected through the heating chamber and escapes through the opening at the end thereof. I introduce also into the heating chamber, through openings formed in the walls thereof, an additional supply of air which appears to combine with the blue flame within the heating chamber so as to increase the heating effect. I find by actual experiment that if an added supply of air is not introduced to the blue flame within the heating chamber, the heating effect is not so pronounced as when this is done and there is also danger of carbonization around the mouth of the tip, particularly if the gas pressure is low. The outer end of the tip is preferably formed as a bead or button, which becomes highly heated by the blue flame and which constitutes the re-lighting device and serves to strengthen the tip. In practice, I find that this enlargement at the end of the tip frequently becomes red hot so as to glow and it operates very effectively to re-light the flame should it become extinguished. Preferably, I form a series of openings in the wall of the heating chamber immediately below this enlargement,

ment, which openings by restricting the paths of heat conduction, permit the large end to be heated more effectively. Under some conditions very small tongues from the blue flame are forced out through these latter openings in operation so as to increase the heating effect. 70

In order that my improved method may be better understood, attention is directed to the accompanying drawing showing a sectional view on a greatly enlarged scale of a burner tip suitable for use with a miner's lamp and with which the method may be conveniently carried out. This tip is made of any suitable refractory material, preferably the so-called lava, of which gas tips are now made. It comprises a tapered nipple A, by which the tip is frictionally supported in any suitable way at the outer end of the gas pipe. The nipple is formed with a bore B and with a very small gas orifice C, the diameter of which determines the capacity of the tip. Above the orifice C is a larger passage D, into which lead the air openings E E to supply a limited amount of air to the gas stream projected through the orifice C, thus producing a so-called Bunsen effect, the gas stream igniting immediately above the mouth of the enlargement D. The main portion of the tip comprises the heating chamber F having tapered walls as shown so as to be as strong as possible and at the extreme end is formed with a bead or button G. The outer end of the heating chamber is contracted as shown, forming an opening H, through which the blue flame projects and above which the illuminating flame is formed. An additional supply of air is introduced within the heating chamber through openings I and J which may be located in any suitable way; and immediately below the bead or button G I form other openings K which serve the purpose of restricting the path for the escape of heat from the bead or button so that the latter is more effectively heated and which also permit small tongues from the blue flame to be forced out around the bead or button so as to increase the heating effect. In the drawing I illustrate the blue flame in dotted lines by the letter a, and the illuminating flame in full lines by the letter b. 100

The indication of the blue flame is not intended to be precisely exact because its conditions appear to be constantly changing according to the variations in pressure. Sometimes the blue flame appears to exist as a very thin pencil of substantially the same diameter throughout, located centrally in the heating chamber, and at times when the pressure is low it appears to swell outwardly so as to occupy the entire bore of the forward portion of the heating chamber and small tongues are forced out through the openings K and it varies between these two extremes. 115 120 125 130

In operation, assuming such a tip as I have described to be used with a miner's lamp and that gas under a slight pressure is being forced through the minute orifice 5 C, the gas stream will be ignited at about the level of or slightly beyond the mouth of the enlargement D so as to burn as a blue flame within the heating chamber. When supplied with an additional amount of air 10 as described, the heating effect is very pronounced and in a short time the heating chamber will become very hot and the bead or button G will be intensely heated, sufficient to re-ignite the gas in case it becomes 15 extinguished. The flame projects through the aperture H and beyond the tip it will burn as a luminous flame of great intensity corresponding in all respects to the flames now used.

20 I am not able to state positively what chemical action takes place in burning acetylene gas as I have above described in two separate distinct zones. It is possible that the combustion taking place in the heating 25 chamber is an incomplete combustion which is completed outside of the tip to form the illuminating flame b. On the other hand, it is possible that a certain amount of unconsumed acetylene is carried by the blue 30 flame through the tip and becomes ignited on the outside of the tip to form the illuminating flame, or that both of these actions take place. Whatever may be the explanation of the phenomena, I find that by carrying 35 my method into effect I am enabled to obtain within the heating chamber a blue flame having little or no tendency to carbonization, which is sufficiently hot to raise the re-lighting device to the proper temperature 40 and that after leaving the tip an illuminating flame is secured, substantially corresponding in intensity and length to the usual standards. In practice I have determined that the best results are secured by 45 carrying out the improved method with a device having the features shown in the drawing; but obviously the tip may be varied to meet the varying conditions of gas pressure, etc. It is desirable to contract the 50 discharge from the heating chamber as shown because in this way the best heating effect is secured. I find, however, that if the opening H is enlarged somewhat, sufficient heating may be secured to re-light the flame.

55 The size of this opening depends upon the gas pressure and the size of flame desired and should be made small enough to secure a slight backing up of the flame within the heating chamber and not too large as to be 60 ineffectively heated. The size and dimensions of the heating chamber also determine the heating effect and I have found by experiment that if the heating chamber is made too short it will be ineffectively heated.

65 Not only does the improved method pro-

vide a way by which the flame will be automatically and immediately re-lighted if it becomes extinguished, but by causing the flame to be divided into two zones as shown and by confining the heating zone within a 70 more or less closed chamber the flame as a whole is effectively protected from blasts and drafts of air. In other words, I find that with a tip such as described when subjected to blasts of air, the flame instead of being 75 immediately extinguished as is the case with the usual tips, is not only protected by the walls of the heating chamber but may actually burn from one or more of the openings I, J or K on the side of the tip opposite 80 to the direction of the blast.

The tip could be made of other materials but is preferably of material which is heat retentive but which will not readily conduct heat. Material, commercially referred to as 85 lava, and already mentioned herein, has these properties and is very desirable. In tips constructed of this material in accordance with my invention the head or bead becomes so hot and the heat is so retained that the 90 gas will be re-ignited several seconds after extinguishment of the flame, whereas the base of the tip remains so cool that a match applied thereto will not ignite. This will prevent heating of supports or fixtures in 95 which the tips are used.

Having now described my invention, what I claim as new therein and desire to secure by Letters Patent is as follows:

1. The method of burning acetylene or 100 similar hydrocarbon gases for illuminating purposes, which consists in projecting a gas stream through a restricted orifice, in igniting the same, in subdividing the resulting flame into two defined zones, one of which 105 is non-illuminating and non-carbonizing and the other of which is an illuminating zone, and in causing the non-illuminating zone to heat a body of refractory material with which the gas stream when not ignited 110 comes into close proximity or contact, whereby the gas stream will be ignited, as and for the purposes set forth.

2. The method of burning acetylene or 115 similar hydrocarbon gases for illuminating purposes, which consists in projecting a gas stream through a restricted orifice, in igniting the same, in subdividing the resulting flame into two distinct zones, one of which 120 is non-illuminating and non-carbonizing, and the other of which is an illuminating zone, in causing the flame to be projected through an annular body of refractory material at or about the dividing line between the two zones, whereby said annular body will be heated by the non-illuminating flame to ignition temperature, as and for the purposes set forth.

3. The method of burning acetylene or 130 similar hydrocarbon gases for illuminating

purposes, which consists in igniting a constricted gas stream so as to produce an elongated flame, in feeding to the flame at its base a sufficient supply of air only to produce a non-illuminating and non-carbonizing zone therein, in causing the non-illuminating section of the flame to impart heat to a body of refractory material located sufficiently close to the gas stream as to ignite the same, and in supplying sufficient air to the flame beyond the refractory material as to make the flame luminous, as and for the purposes set forth.

4. The method of burning acetylene or similar hydrocarbon gases for illuminating purposes, which consists in projecting a gas stream through a restricted orifice, in feeding a limited supply of air to the gas stream at its base so that when the gas stream is ignited a substantially prolonged non-illuminating zone will be secured, in adding to the gas stream a further supply of air within the heating chamber, and in projecting the flame through an opening in the heating chamber to burn outside of the same as a luminous flame, the walls of the

heating chamber adjacent to said orifice being heated by the non-illuminating section of the flame to the ignition temperature, as and for the purposes set forth.

5. The method of burning acetylene or similar hydrocarbon gases for illuminating purposes, which consists in projecting a gas stream from a restricted orifice and igniting the same, in causing the resulting flame to be projected through an annular body of refractory material whereby the flame will be contracted at a point between its extreme ends, in feeding to the flame between its origin and the contracted portion thereof a limited air supply to produce a non-illuminating zone which heats the annular body to the ignition temperature, and in supplying to the flame between the contracted portion and its outer end a further supply of air to produce a luminous zone, substantially as and for the purposes set forth.

In witness whereof I hereunto subscribe my name this 22nd day of November, A. D., 1916.

AUGIE L. HANSEN.
